(57) **CLAIM**

The ornamental design for an apparatus for producing advanced oxidation products, as shown and described.

DESCRIPTION

FIG. 1 shows a perspective view of the apparatus for producing advanced oxidation products;

FIG. 2 shows a front elevation view thereof;

FIG. 3 shows a left side elevation view thereof;

FIG. 4 shows a right side elevation view thereof;

FIG. 5 shows a rear elevation view thereof;

FIG. 6 shows a top plan view thereof; and,

FIG. 7 shows a bottom plan view thereof.

The broken lines of FIG. 1 to FIG. 7 illustrate portions of the apparatus for producing advanced oxidation products that form no part of the claimed design.
